UNITED STATES PATENT OFFICE.

PAUL P. BARTMER, OF DENVER, COLORADO.

LOCK FOR THE HOODS OF AUTOMOBILES.

1,208,893.

Specification of Letters Patent. Patented Dec. 19, 1916.

Application filed August 12, 1916. Serial No. 114,612.

To all whom it may concern:

Be it known that I, PAUL P. BARTMER, a subject of the Czar of Russia, residing in the city and county of Denver and State of Colorado, have invented a new and useful Lock for the Hoods of Automobiles, of which the following is a specification.

My invention relates to locks for the hoods of automobiles, and the objects of my invention are, first, to provide locks for the opposite sides or corners of hoods of automobiles that can only be released from the inside of the dash board of the automobile; and second, to provide locks for the hoods of automobiles that when locked cannot be unlocked and the hood raised except when the driver or owner is present or his hood key is obtained from him. I attain these objects by the mechanism illustrated in the accompanying drawings, in which:

Figure 1 is a view, partly in section and partly in side elevation, of the improved lock, the bolt thereof being shown engaged by the latch. Fig. 2 is an elevation, partly in section, showing the manner of securing the lower member of the lock to the side bar of the car, the upper member being connected to the hood. Fig. 3 is a plan view showing a portion of one of the side bars 25 of a car, a portion of the hood, and the lock attached to the said hood and side bar. Fig. 4 is a vertical longitudinal sectional view through the hood and dash board of a car, showing the manner of unlocking the locks simultaneously by a hand lever mounted on said dash board. Fig. 5 is a transverse vertical sectional view through the hood and side bars, showing the manner of connecting the latch operating chains or cables with the operating lever mounted on the dash board. Fig. 6 is a horizontal sectional view through one side of the hood showing the locks and the connections extending therefrom to the operating lever; and Fig. 7 is 45 a front view showing the manner of locking the operating lever.

Similar letters of reference refer to similar parts throughout the several views.

Referring to the drawings: The numeral 50 1 designates the side bars of an automobile; 2 designates the hood and 3 the dash board. These parts are common to all makes of automobiles and the improved lock is adapted to conform to the difference in the detail 55 construction and arrangement of these parts

of the several automobiles on the market, in the most convenient manner.

The lock consists of two parts, a fixed socket or barrel 4 that forms the body of the lock and which is attached to the side 60 bar of the automobile, and a movable part which forms the bolt 5 of the lock and which is mounted in a housing 6 which is secured to the inside surface of the hood.

The fixed member of the improved lock 65 consists of a cylindrical casing or barrel, the lower end of which is provided with a removable cap 7 that is threaded to it, and which is provided with a hexagonal wrench-receiving member 8. The opposite end of 70 the cylinder is provided with a flange 9, which is provided with apertures for the reception of bolts 10, which pass through the said apertures and also through registering apertures in the side bar 1, nuts 11 75 being threaded to said bolts thereby to secure the member 4 to the said side bar.

To the underside of the flange 9 and in line with the axial center of the barrel or socket 4 is secured a housing 12, in which 80 is slidably mounted a latch 13, having a shoulder 14, between which and the outer end of the housing is interposed a coil spring 15, which surrounds the said latch and normally holds the same in position to 85 engage the bolt. The outer end of the housing 12 is slotted and a pin X extends through the latch 13 and into the slot, thereby preventing the latch from turning. This pin X also limits the inward movement of the 90 latch, with respect to the barrel. The latch extends through its housing and through a hole in the shell of the barrel 4 and its inner end is arranged to engage annular locking grooves 16 formed on the bolt 5 when the same is inserted in the barrel. The barrel 4 has a bore of two diameters. That part having the greater diameter extends substantially two-thirds of the length of the barrel from its lower end, and the remainder 95 of the bore is of less diameter or of the same diameter as the bolt 5. A shoulder 17 is formed at the junction of the two bores and when the bolt 5 is locked within the barrel its lower portion, which is slightly tapered, 100 extends down below the said shoulder 17 and its lower end is engaged by a cylindrical block 18 which is forcibly held against the said end by an air expansion coil spring 19 which is housed in the barrel, between the 105

said block and the cap 7. When the latch 13 is withdrawn to release the bolt 5, the said bolt is thrown clear of the latch by the spring actuated block 18, which then rests 5 against the shoulder 17 until the bolt is again inserted in the barrel and locked therein.

The hood attached part of my lock comprises the cylindrical housing 6, upon which 10 is formed a plate 20 that is secured to the hood by any suitable means, preferably by screws or rivets. The coupling pin or bolt 5 is reciprocally mounted in the housing 6, and a coiled spring 21 is mounted on a reduced portion of the said bolt and bears 15 against a shoulder 22 formed adjacent to its upper end and at its opposite end against a nut 23 that is threaded to the lower end of the housing 6, the nut having an aperture 20 through which the coupling bolt passes.

The coupling bolt has a short compensating movement in the casing that permits the cylindrical body portion to draw and hold the hood down against the frame with a resilient pulling tension that holds the hood firmly and tightly against the frame and obviates any possible rattling of it when the car is running. In order that the coupling bolt may lock readily to the barrel 4, it is provided with several locking grooves 16, three being shown, which are spaced a short distance apart above the tapered portion of the bolt and permit of the attachment of the parts of the lock to the hood and frame of 35 different makes of cars in such relative positions that one of the grooves 16 will be engaged by the latch 13 and thus lock the bolt 5 to the barrel 4. I preferably place four of these locks on a hood of an automobile, 40 one at each corner, but if desired only two may be used, one at each of the central portions of the opposite sides of the hood.

To assist in raising and also locking the sides of the hood I provide the upper end 45 of the bolt 5 with a finger grasping stem 24 that extends through a slot 25 formed in the side of the housing 6 and also through a slot 25^A in the hood, which latter slot is partially covered up by a flange portion 50 26 that is formed on the stem and that extends beyond the slot over onto the outside surface of the hood. The slot 25 permits the stem to slide up and down to the extent of the compensating movement of the coupling bolt 5. Consequently each side of 55 the hood can be lowered and locked by hand by simply pushing the coupling bolts on each side down into the barrels 4 until the latch 13 springs into one of the grooves of the 60 coupling bolt, it being assumed that in attaching the two parts of the lock to the opposite sides of the hood and frame, they are arranged in alinement with each other and in such relative positions that the side 65 edges of the hood will bear down against

the frame of the automobile. A plate 6^A is mounted in a slideway in the face of the plate 20, so as to cover the slot 25; the pin 24 passes through a hole in this plate and when the bolt 5 is moved up or down the plate 6^A is also moved. This plate always covers the slot 25 and thus prevents dust and grit from entering the housing. The edges of the plate are beveled, and the edges of the slideway are correspondingly undercut, thus preventing the plate from becoming detached from the slideway.

One of the essential features, however, of the invention is to have the locking bolts operated to unlock both sides of the hood 80 from the inside of the dash board of the car, and the invention contemplates broadly any means by which this object may be obtained. The locks are therefore arranged so that they cannot be unlocked except from the 85 inside of the dash board, and the hood unlocking mechanism that is placed inside of the dash board is arranged to be locked by the owner or chauffeur or driver of the car when he leaves it in a garage or on the street 90 or anywhere out of his sight, so that the hood cannot be unlocked and its sides raised and the engine or its coöperating mechanism that is within the hood tampered with; and while there are a number of ways in 95 which this feature of my invention may be carried out, I preferably use the following instrumentalities in effecting it: Each latch 13 is provided with an apertured head 27 at its end, to which one end of a cord or 100 chain 28 is secured; the chain or cord of each forward latch being secured to the latch of the rear lock on that side, as will be understood by reference to Fig. 6, so that a pull on the rear latch will effect a simultaneous pull on the forward latch. The cords or chains 28 pass under pulleys 29 and over pulleys 30, and the end of one of the cords is secured to one end of a centrally mounted and vertically disposed rock 110 lever 31, while the end of the other cord is secured to the other end of the lever 31, as will appear by reference to Fig. 5. The lever 31 is rigidly secured to one end of a bearing pin 32, which is pivotally mounted 115 in the dash board, and which is rigidly secured to or forms an integral part of a hand lever 33, which is located within convenient reach of the driver of the car. It will thus be seen that by turning the lever 120 31 in the direction of the arrow (see Fig. 5) both cords 28 are drawn upon simultaneously and all of the latches 13 are withdrawn, thereby allowing the spring operated blocks 18 in the barrels 4 to shoot the bolts 125 5 clear of the latches 13; the lower notches 16 of the bolts being farther from the end of the bolt than the distance between the shoulders 17 and the latches 13, so that when the blocks 18 are forced up against 130

the shoulders 17 by the springs 19, the latches could not engage the lower notches 16 if the ends of the bolts should then rest upon the blocks 18, as the said notches will 5 be on a higher plane than the latches 18.

The lever 33 may be locked in any preferred way. In the drawings, however, the lower end of this lever is provided with an aperture which registers with a corresponding aperture in an angle plate 34, which is bolted to the dash board. The lever 33 is then secured to the angle plate 34 by a padlock, as shown in Fig. 7, and thus any tampering with the locks by an unauthorized 15 person is prevented.

Having described my invention, what I claim as new and desire to secure by Letters Patent is:

1. A dash releasing lock for the hoods of automobiles, comprising a two-part lock, the parts of which are adapted to be secured to the hood and the frame of an automobile, said parts being provided with a coupling pin and a locking bolt adapted to lock to 20 each other, one of said locks being placed at each corner portion of the hood, flexible members extending from the locking bolt of each lock to the inside of the dash, and means under the control of the driver of 30 the car for moving the locking bolt to unlock the coupling pin and release the hood from the frame.
2. A dash releasing lock for the hoods of automobiles, comprising the combination of a two-part lock placed at each corner of the opposite sides of the hood, one part of which is secured to the hood and the other part is secured to the frame, the part on the hood having means including a coupling pin 35 for entering the part on the frame, a locking bolt on the part of the frame arranged to lock to said coupling pin, and means including flexible members connected to the locking bolts of each lock and extending to the inside of the dash, and means including a lever under the control of the driver and connected to said flexible members for moving said locking bolt to release said coupling pin and free said hood from the frame.

3. In a dash releasing lock for the hoods of automobiles, the combination with the hood and the dash, of a lock comprising two connecting body portions, one of which connects to the hood and the other to the frame 55 of an automobile, each of which is provided with locking members that are spring controlled in one direction of their operative movements, means by which the locking member of each part locks to the other part 60 and means including a hand operating member connected to the inside of the dash by which the driver may release the locking members to unlock the hood from the frame.

4. In a dash releasing lock for automobiles, the combination of the hood, the dash

and the frame, with a lock comprising two parts, one of which is attached to the hood and the other to the frame, a resiliently arranged coupling pin mounted in the part on the hood arranged to extend into the 70 part on the frame, a locking bolt therein arranged to lock the coupling pin to the part on the frame, and means including a hand operating device attached to the dash board and connected to the locking bolt of 75 the frame for unlocking the lock and releasing the hood from the frame.

5. In a device of the character described, the combination with the hood and frame of an automobile, of locking means for said 80 hood, comprising barrels secured to said frame, bolts carried by said hood and adapted to enter said barrels, spring actuated latches carried by said barrels for engaging said bolts, manually operated 85 means for simultaneously withdrawing said latches, and a lock for said manually operated means.

6. In a device of the character described, the combination with the side bars, the dash 90 board and the hood of an automobile, of means for locking said hood to said side bars, comprising barrels secured to said side bars, spring actuated latches carried by said barrels, bolts carried by said hood which 95 are adapted to enter said barrels and be engaged by said latches, a lever mounted in said dash board, flexible connections extending from said latches to said lever which are adapted to be drawn upon simultaneously 100 to withdraw said latches and release said bolts, and means for locking said lever.

7. The combination with the side bars, the dash board and the hood of an automobile, of means for locking the hood to the 105 side bars, comprising barrels secured to said side bars, annularly grooved bolts carried by said hood, and adapted to enter said barrels, spring controlled latches carried by 110 said barrels for engaging said grooved bolts, a lever mounted in said dash board, flexible means connecting said latches and said lever, whereby the latches are simultaneously withdrawn when the lever is turned, spring operated blocks carried by the barrels for 115 throwing the bolts clear of the latches when the said latches are withdrawn, and a lock for said lever.

8. The combination with the side bars, the dash board and the hood of an automobile, of means for locking the hood to the 120 side bars, comprising socket members which are secured to said side bars, housing members secured adjacent to the corners of said hood, and bolts resiliently mounted in said 125 housings, having annular latch receiving grooves, said bolts being adapted to enter said sockets, spring actuated latches mounted on said socket members for engaging said grooved bolts, a lever mounted in the dash 130

board and flexible members connecting said lever and latches, whereby the latches are simultaneously withdrawn when the lever is operated, expansion coil springs in the lower 5 ends of said socket members, blocks which rest on said springs and are depressed by the ends of said bolts when the same are locked and act to throw the bolts clear of the latches when the latches are operated 10 to release the bolts, means for limiting the upward movement of said blocks, and a lock for said lever.

9. A lock for the hoods of automobiles, comprising a barrel adapted to be secured 15 to the frame of the automobile, and having a bore of two diameters, a shoulder being formed at the junction of the two diameters, a threaded cap on the lower end of said barrel, an expansion coil spring in said barrel, a block in said barrel adapted to be thrown upward against said shoulder by 20

said spring, a spring actuated latch secured to said barrel, which is normally projected into the smaller bore of said barrel, a housing adapted to be secured to the hood of the 25 automobile having a slot in one side and an apertured cap threaded to its lower end, a bolt having annular latch-receiving grooves, the upper portion of which lies in said housing and has a shoulder adjacent 30 to its upper end, a coil spring which is interposed between said shoulder and the apertured cap, and a pin extending through said slot and threaded to said bolt, said bolt being adapted to enter said barrel, depress 35 said block and be engaged by said latch.

In testimony whereof I affix my signature in presence of two witnesses.

PAUL P. BARTMER.
